US00D734432S

(12) **United States Design Patent**
Sato et al.

(10) **Patent No.:** US D734,432 S
(45) **Date of Patent:** ** Jul. 14, 2015

(54) **PINCH VALVE**

(71) Applicants: **Hideharu Sato**, Tsukubamirai (JP);
Yoshitada Doi, Tsukubamirai (JP);
Masato Aoki, Tsukubamirai (JP)

(72) Inventors: **Hideharu Sato**, Tsukubamirai (JP);
Yoshitada Doi, Tsukubamirai (JP);
Masato Aoki, Tsukubamirai (JP)

(73) Assignee: **SMC Corporation**, Chiyoda-ku, Tokyo (JP)

(**) Term: **14 Years**

(21) Appl. No.: **29/502,116**

(22) Filed: **Sep. 11, 2014**

(30) **Foreign Application Priority Data**

Jun. 30, 2014 (JP) 2014-014221
